UNITED STATES PATENT OFFICE

157,140

COMBINED IRONER AND STAND

John J. Getgey, Cincinnati, Ohio, assignor to
Empire Ironer, Inc., Cincinnati, Ohio, a corpo-
ration of Ohio

Application December 19, 1947, Serial No. 143,233

Term of patent 7 years

(Cl. D49—6)

To all whom it may concern:

Be it known that I, John J. Getgey, a citizen of the United States, residing at Cincinnati, in the county of Hamilton and State of Ohio, have invented a new, original, and ornamental Design for a Combined Ironer and Stand, of which the following is a specification, reference being had to the accompanying drawings, forming a part thereof.

Figure 1 is a perspective view of a combined ironer and stand showing my new design.

Figure 2 is a top plan view of the stand.

Figure 3 is a front view of the stand.

Figure 4 is an end view of the stand.

The dominant features of my design reside in those portions shown in full lines.

I claim:

The ornamental design for a combined ironer and stand, substantially as shown and described.

JOHN J. GETGEY.
